UNITED STATES PATENT OFFICE.

JACOB COHN, OF NEW YORK, N. Y., ASSIGNOR, BY MESNE ASSIGNMENTS, TO NON-EXPLOSIVE CORPORATION OF AMERICA (NEW CORPORATION), A CORPORATION OF DELAWARE.

SAFETY ATTACHMENT FOR TANKS.

Application filed July 26, 1924. Serial No. 728,337.

The present invention relates to improvements in safety attachments for tanks and has for an object to provide for the venting of excess pressure from the tank while also 5 permitting of the entry of air to relieve any partial vacuum forming in the tank as when drawing off the contents.

The invention further contemplates the use of a counter balance structure in which 10 vibration will be avoided and which will be accessible for adjustment on the exterior of the tank.

A further object of the invention contemplates providing an enlarged bearing 15 surface for the pressure relief valve in order to permit the relief valve to accommodate itself to its seat and thereby insure a tight fit during the closing of the valve.

With the foregoing and other objects in 20 view, the invention will be more fully described hereinafter, and will be more particularly pointed out in the claim appended hereto.

In the drawings, wherein like symbols 25 refer to like or corresponding parts throughout the several views,

Figure 1 is a top plan view of a device constructed according to the present invention, and

Figure 2 is a side view thereof with parts shown in section.

Referring more particularly to the drawings 3 designates the tank wall provided with the threaded opening 4 to receive the bushing 5 which projects above and below the tank wall. The skirt portion 6 within the tank is adapted to receive the foraminous or reticulated cylinder composed preferably of a perforated metal 7 with wire mesh 8 on both sides thereof; or perforated metal may be placed on opposite sides of the central wire screen and the device is supported from the skirt as by pressing the metal into the annular groove 9 on the exterior thereof.

The upper projecting part of the bushing is provided with an elongated frusto-conical valve seat 10, the section of the cone on which the same is taken being inverted. The valve seat 10 cooperates with a complementary elongated and frusto-conical surface upon a hollow relief valve body 11 which extends above the bushing and is provided in its upper part with openings 12 through which air from the atmosphere freely passes

to the large interior space of the valve body. 55 The bottom portion of the valve body beneath the conical seat is entirely open leaving a relatively wide area to be normally closed by a disc valve 13, there being mutual seating surfaces, preferably inclined, as indicated at 14 between the peripheral edge of the disc valve and the lower open edge of the valve body. The disc or air valve 13 is carried upon the stem 15 which projects through the cylindrical guide 16 carried centrally within the relief valve body 11 and depending from the top thereof. The lower end of the guide cylinder 16 is closed by a threaded plug 17 through which the valve 70 stem 15 freely slides, and a plunger 18 provided with air ports 19 is mounted to reciprocate in the guide cylinder and secured to the upper end of the valve stem. The piston and guide cylinder form in effect a dash 75 pot to prevent the chattering of the valve and the plunger 18 subserves the further function of acting as an abutment for the upper end of the coil spring 20, the lower end of which bears against the plug 17. The function of this spring is to maintain 80 the plunger in the raised position and the air valve 13 closed against its seat 14.

The air valve is therefore carried by the relief valve body 11 and the two constitute a unitary structure. The accumulated pressure in the tank will act beneath the wide surface of the air valve 13 and will raise the relief valve from the seat 10 permitting of the escape of pressure while the atmosphere has an equally wide area to exert its pressure 90 against upon the upper surface of the relief valve 13, so that when any pressure below that of atmospheric pressure occurs in the tank, the air valve 13, will open and admit air to relieve the tendency to a partial vacuum. 95

This unitary device is counter balanced and to this end I provide a rigid stud 21 projecting from and axially of the relief valve body 11. The stud is adapted to reciprocate through a bearing 22 supported by the spider arms 23 which are secured as by means of the screws or other fastenings 24 to a flange 25 of the bushing 5 which flange also acts to compress a gasket 26 to avoid the leakage of pressure from the tank about the bushing threads. The upper end of the stud 21 is threaded to receive a cross head 27 provided with divergent forked arms 28 and 29 sup-

porting pins 31 which slide in the slots 31' of the counter weight levers 32. The slots open mutually toward one another upon the ends of the levers so as to permit the ready assembly of the parts. The levers 32 are fulcrumed as indicated at 33 upon the horns 34 which may be made apart of the spider arms. The counter weights 35 slide upon the outer ends of the levers 32 and are threaded to engage the threaded adjusting rods 36. The adjusting rods are fixed against longitudinal movement in collars 37 upon the arms but they are free to rotate and on rotation thereof the weights are shifted either toward or from the pivot points 33 to vary the counter balancing action.

In the use of the device the parts are assembled upon the tank as shown in Figure 2, the entire assembly being upon the bushing 5 which is secured into the opening in the tank wall. The spring 20 and counter balance weights are selected and adjusted to suit conditions of use, so that the relief and air valve will open upon the desired pressure. Any pressure accumulating within the tank will pass through the mesh and perforations of the safety cylinder and accumulating beneath the air valve will lift the relief valve and permit escape thereof, while the atmospheric air will be admitted through the air valve when a suitable degree of vacuum occurs in the tank. By adjusting the weights 35 the degree of pressure upon which the relief valve will open may be regulated and

it will be understood that the stud 21 is rigid and partakes of a rectilinear movement through the bearing 22, so that the movement is directly transmitted to the levers and no lost motion occurs and no lateral vibration may take place in this stud.

The enlarged valve surface 10 permits the valve to accommodate itself to the wide area and to insure tight seating.

It is obvious that various changes and modifications may be made in the details of construction and design of the above specifically described embodiment of this invention without departing from the spirit thereof, such changes and modifications being restricted only by the scope of the following claim.

What is claimed is:—

In combination with a receptacle, a relief valve, an air valve carried by said relief valve, a yoke member having horns detachably affixed to said receptacle, a rigid stud attached to the top of said relief valve and adapted to reciprocate in said yoke upon the movement of said relief valve, a cross head with divergent arms detachably affixed to the top of said stud above the yoke, weighted levers fulcrumed at a point intermediate their ends to the horns of said yoke and having the near ends thereof provided with slots opening through such ends, pins carried by said divergent arms slidably and detachably engaged in said slots.

JACOB COHN.
